United States Patent Office

Des. 185,754
Patented July 28, 1959

185,754

COMBINATION CLOSURE CAP AND POURING SPOUT

Calvitte L. Jones, Brookfield, and James B. Taylor III,
Fairfield, Conn., assignors, by mesne assignments, to
American Flange and Manufacturing Co., Inc., New
York, N.Y., a corporation of Delaware

Application April 4, 1958, Serial No. 50,340

Term of patent 14 years

(Cl. D58—26)

FIG. 1

FIG. 2

FIG. 3

Fig. 1 is a perspective view of a combination closure cap and pouring spout showing our new design;

Fig. 2 is a top plan view thereof; and

Fig. 3 is a side elevational view thereof.

We claim:

The ornamental design for a combination closure cap and pouring spout, substantially as shown.
